UNITED STATES PATENT OFFICE

168,166

BUBBLE BLOWING DEVICE

Harry Margolis, Brooklyn, N. Y.

Application June 4, 1952, Serial No. 20,028

Term of patent 7 years

(Cl. D34—15)

To all whom it may concern:

Be it known that I, Harry Margolis, a citizen of the United States, resident of Brooklyn, in the county of Kings, city and State of New York, have invented a new, original, and ornamental Design for a Bubble Blowing Device, of which the following is a specification, reference being had to the accompanying drawing, forming part hereof.

In the drawing:

Figure 1 is a front view of a bubble blowing device showing my new design.

Figure 2 is a side view thereof.

Figure 3 is a top view thereof, and

Figure 4 is a bottom view thereof.

I claim:

The ornamental design for a bubble blowing device, substantially as shown.

HARRY MARGOLIS.
